UNITED STATES PATENT OFFICE.

FRANK BISHOP, OF OGDEN, UTAH TERRITORY.

ORE-CRUSHER.

SPECIFICATION forming part of Letters Patent No. 519,228, dated May 1, 1894.

Application filed May 31, 1893. Serial No. 476,008. (No model.)

To all whom it may concern:

Be it known that I, FRANK BISHOP, of Ogden, in the county of Weber and Territory of Utah, have invented a new and Improved 5 Ore-Crusher, of which the following is a full, clear, and exact description.

The invention relates to machines for crushing and pulverizing gold, silver or other ores, &c., and its object is to provide a new 10 and improved crusher which is simple and durable in construction and very effective in operation.

The invention consists of certain parts and details, and combinations of the same, as will 15 be hereinafter described and then pointed out in the claims.

Reference is to be had to the accompanying drawings, forming a part of this specification, in which similar letters of reference indicate 20 corresponding parts in all the figures.

Figure 1 is a plan view of the improvement with parts broken out. Fig. 2 is a sectional side elevation of the same on the line 2—2 of Fig. 1. Fig. 3 is a sectional side elevation of 25 one of the scrapers. Fig. 4 is a plan view of the base and the means for imparting a rotary motion to the revoluble bed. Fig. 5 is an inverted plan view of the revoluble bed; and Fig. 6 is a sectional face view of one of 30 the crushing rollers.

The improved crusher is provided with a base A supported on a foundation A' and carrying sets of posts B in which are journaled the shafts C, C', C², C³, of which the 35 shafts C, C' carry on their outer ends pulleys D and D' respectively, connected by belts D² and D³ with pulleys D⁴ and D⁵ secured on the line shaft D⁶ connected with suitable machinery for imparting a rotary motion to the 40 said shaft D⁶.

On each of the shafts C, C', C², and C³ and between the two posts of the corresponding set is secured a step pulley E, engaging at 45 its top steps F', formed circularly on the under side of the ring-shaped bed F having a top facing F², on which the crushing of the ore or stone takes place. It is understood that the bed F is horizontally disposed and rests on several step pulleys E arranged in 50 the sets of posts B, as above described.

As shown in Figs. 1 and 2, four shafts and corresponding step pulleys are provided, the

several shafts extending radially from a center which is the center for the bed F, and also for the annular steps F' engaging the step pulleys E. On the under side of the bed F and near the outer edge of the same is secured a gear wheel G, in mesh with gear wheels H, attached on the shafts C and C' next to the base ends of the pulleys E carried by the said shafts. 55 Now, it will be seen that when the shafts C and C' are rotated, the gear wheels H will impart a rotary motion to the bed F supported on the pulleys E which also tend to impart a forward motion to the bed. On the 60 top of the facing F² of the latter is formed a series of concentric annular grooves F³, approximately V-shaped and adapted to be engaged by correspondingly shaped ridges formed on rims I, bolted or otherwise secured 65 to the rim of rollers J, secured on shafts K, journaled in boxes L, mounted to slide vertically in the upper ends of the sets of the posts B directly above and in line with the corresponding shafts C, C', C² and C³ journaled in the lower ends of the respective posts, 70 as before described.

On top of the bearings L press the springs N, the tension of each being regulated by a set screw O, screwing in the upper ends of 75 the posts and abutting on the top of the corresponding spring. Thus, when the material is treated, the individual roller J can move upwardly, its bearings L moving against the tension of the corresponding springs N. As 80 shown in Figs. 1 and 2, the rims I and rollers J are inclosed at their upper half in a suitable casing P, held on a base P' bolted or otherwise secured to the posts B.

The bed F is provided with an outer annular flange F⁴ flaring outwardly and upwardly as plainly shown in Fig. 2, and a similar flaring flange F⁵ is arranged on the inner side of the said bed F. A circular screen Q, and a rim Q' are attached to the upper ends 95 of the said flanges F⁴ and F⁵ respectively, and extend vertically under flanges P² and P³ depending from the base P' carrying the hoods P.

Scrapers R are suspended from the stationary casings P in front of the latter, the said scrapers extending from the exterior flange F⁴ of the bed F inwardly over the corrugated facing F² to guide the material onto the latter. 100

- In the base P' are feed openings P⁴ through which the material is introduced to the facing of the bed F to be crushed by the rollers J. The material is conveyed by conveyers S to the said feed openings P⁴ from a hopper T into which discharges the material supply chute U. The screw shafts of the conveyers are driven by suitable pulleys and belts from the line shaft D⁶. The lower edge of the screen Q extends into semi-ring shaped receiving spouts or troughs V and V', inclined toward each other and provided at their lowest ends with discharge spouts V² leading to the settling tanks W.
- 15 The operation is as follows: When the several parts are in the position shown in Fig. 2 and a rotary motion is imparted to the several shafts C, then the bed F is revolved, as previously described and the material fed by the conveyers S onto the bed-facing F² and into the annular V-shaped grooves F³, to be carried under the rims I and consequently crushed by the frictional contact of the rollers J with the V-shaped grooves on the facing of the bed F. It will be seen that the pressure of the crushing rollers J can be increased or diminished by regulating the tension of the springs N by the set screws O, so that the said rollers press with more or less force onto the material passing between the rollers, and the facing of the bed. The crushed material is thrown by the centrifugal force of the revolving bed F against the screen Q, and if crushed sufficiently fine passes through the meshes of the screen to drop into the troughs V and V' from which the crushed material passes to the tank W to be further treated. The larger material not passing through the meshes of the screen Q, falls downward on the inside of the screen onto the flange F⁴ to be finally guided back into the grooves of the bed facing F² by the aprons R to be again subjected to the crushing process of the rollers, as above described.
- 45 It will be seen that a machine constructed in this manner is not liable to get out of order, as it is composed of but few parts. It will further be seen that it requires but little power to run the machine for crushing a large amount of ore or other material.
- Having thus fully described my invention, I claim as new and desire to secure by Letters Patent—
1. A crusher, comprising a bed having steps formed on its under side and mounted to revolve on step pulleys, and rollers arranged over the bed, substantially as set forth.
  2. A crusher, comprising a bed having steps formed on its under side and mounted to revolve on step pulleys, screens secured to the outer edge of said bed, and rollers journaled loosely in yieldingly mounted bearings, the said rollers being arranged over the revolving bed, substantially as described.
  3. A crusher, comprising a bed having steps formed on its under side and mounted to re-
- volve on step pulleys, screens secured to the outer edge of said bed, rollers arranged over the revolving bed, and fixed scrapers for guiding the material to the bed, substantially as shown and described.
4. A crusher, comprising an annular bed mounted to revolve, a screen secured to the outer edge of the said bed, a rim arranged on the inner edge, rollers arranged over the revolving bed and a fixed base carrying covers for the rollers and provided with downwardly projecting flanges to overlap the edges of the screen and rim, substantially as shown and described.
5. A crusher, comprising an annular bed mounted to revolve, said bed being formed with concentric grooves on its top surface, flaring flanges arranged on the outer and inner sides of said bed, upwardly extending screens secured to the outer flange, an imperforate rim secured to the inner flange, rollers formed with ridges to engage the grooves on top of the bed, fixed scrapers extending from the exterior flange of the bed inwardly, and troughs arranged on the outside of said screens, substantially as shown and described.
6. A crusher, comprising an annular bed mounted to revolve, an upwardly extending screen secured to the outer edge of said bed and through which passes the crushed material, an imperforate rim secured to the inner edge of said bed, rollers arranged over the said revolving bed, a fixed base carrying covers for the rollers and having flanges adapted to engage the edges of the screen and rim, said base being provided with feed openings through which the material is delivered to the revolving bed, and conveyers discharging into said feed openings, substantially as shown and described.
7. A crusher, comprising an annular bed having steps formed on its under side and mounted to revolve on step pulleys arranged beneath the said bed, rollers arranged above the bed, sets of posts carrying bearings in which are journaled the shafts of said pulleys, one post of each set being located outside of the annular bed and the other extending upward through the central opening formed by the bed, the upper ends of the said posts carrying yieldingly mounted bearings in which the shafts of the rollers are journaled, substantially as shown and described.
8. A crusher comprising a series of step pulleys, a circular bed formed on its under side with steps engaging the step pulleys, the top of the said bed being formed with V-shaped grooves, and yieldingly mounted rollers formed with V-shaped ridges engaging the said grooves on top of the bed, and means substantially as described, for imparting rotary motion to the said pulleys, substantially as shown and described.
9. In a crusher, the combination with a series of shafts mounted to turn, and each

carrying a step pulley and a gear wheel, of a circular bed formed on its under side with steps engaging the step pulleys, a gear wheel secured to the under side of the said bed, and
5 engaged by the gear wheels on the said shafts, a series of rollers having V-shaped ridges engaging corresponding-shaped annular grooves

on top of the said bed, and spring pressed boxes carrying the shafts for the said ridged rollers, substantially as shown and described.

FRANK BISHOP.
